US00D859147S

(12) **United States Design Patent** (10) Patent No.: **US D859,147 S**
(45) Date of Patent: **** Sep. 10, 2019**

(54) **CARTON BLANK**(71) Applicant: **Graphic Packaging International, Inc.**, Atlanta, GA (US)(72) Inventor: **Kelly R. Fitzwater**, Lakewood, CO (US)(73) Assignee: **Graphic Packaging International, LLC**, Atlanta, GA (US)(**) Term: **15 Years**(21) Appl. No.: **29/617,497**(22) Filed: **Sep. 14, 2017****Related U.S. Application Data**

(60) Continuation of application No. 29/541,969, filed on Oct. 9, 2015, now Pat. No. Des. 800,553, which is a continuation of application No. 29/524,201, filed on Apr. 17, 2015, now Pat. No. Des. 740,657, which is a continuation of application No. 29/469,960, filed on Oct. 16, 2013, now Pat. No. Des. 727,145, which is a division of application No. 29/444,521, filed on Jan. 31, 2013, now Pat. No. Des. 694,106, which is a continuation of application No. 13/046,901, filed on Mar. 14, 2011, now Pat. No. 8,440,947, which is a division of application No. 11/567,364, filed on Dec. 6, 2006, now Pat. No. 7,928,349.

(57) **CLAIM**

The ornamental design for a carton blank, as shown and described.

DESCRIPTION

The sole FIGURE is a plan view of carton blank in accordance with the present invention.

The broken lines shown herein depict environmental subject matter and form no part of the claimed design. The broken line in the form of an alternating series of relatively short dashes and relatively long dashes represents a boundary of the claimed design.
